UNITED STATES PATENT OFFICE

2,449,046

DISPENSING CONTAINER

Wilbur L. Barnes and James J. Harrison, Battle Creek, Mich., assignors to Michigan Carton Company, Battle Creek, Mich., a corporation of Michigan

Application May 9, 1946, Serial No. 668,340

6 Claims. (Cl. 229—17)

1

This invention relates to improvements in dispensing containers.

The main objects of this invention are:

First, to provide a dispensing container, the closures of which are effectively sealed for distribution and quickly opened to provide a pouring opening, such pouring opening having an effective closure.

Second, to provide a structure of this character which may be economically formed with a minimum of waste and the closure flaps closed and sealed on a standard type of sealing machine.

Objects relating to details and economies of the invention will appear from the description to follow. The invention is defined and pointed out in the claims.

A preferred embodiment of the invention is illustrated in the accompanying drawings, in which:

Fig. 1 is a perspective view of a closure embodying the invention with the pouring opening opened.

Fig. 2 is an enlarged fragmentary section on line 2—2 of Fig. 1.

Fig. 3 is an enlarged fragmentary section corresponding to that of Fig. 2 with the closure flaps in their original sealed condition.

Fig. 4 is a fragmentary perspective view illustrating the closure flaps directly involved in the pouring opening in partially open position.

Fig. 5 is a fragmentary perspective view illustrating the inner closure flap turned inwardly and the intermediate and outer closure flaps extended with adhesive conventionally indicated thereon.

Fig. 6 is a fragmentary perspective view illustrating certain of the steps in closing and sealing the closure flaps.

Fig. 7 is an enlarged fragmentary view in section on a line corresponding to line 7—7 of Fig. 3.

Fig. 8 is a plan view of the blank from which the container is formed.

The embodiment of the invention illustrated is a carton of rectangular section formed of container board and comprises the front and rear walls 1 and 2, and side walls 3 and 4, the wall 1 being provided with a sealing flap 5 which is lapped upon and adhesively secured to the wall 4. The terms front and rear and side walls are used for convenience in description.

These walls are provided with bottom flaps 6, 7 and 8, 8 which are folded into overlapping relation and adhesively secured together as is common practice in containers of this type. The wall 2 is provided with a closure flap 9 which

constitutes the inner closure flap of the top of the carton.

The wall 1 has a closure flap 10 constituting the outer closure flap of the carton while the walls 3 and 4 have closure flaps 11 and 12 respectively which constitute intermediate closure flaps. The walls are joined to each other and to their top and bottom closure flaps by hinging scores conventionally indicated at 13.

10 The inner closure flap 9 has a tucking tongue extension 14 on one end thereof, this tongue being cut out of a portion of stock of the intermediate flap 11, as shown in Fig. 8, leaving a notch-like recess 15 therein. The flap 12 has a corresponding recess 16 in the embodiment illustrated but that does not perform any function in this structure illustrated.

15 The flap 9 has a longitudinal fracturing score 17 and transverse fracturing score 18 while the intermediate closure flap 11 has a longitudinal fracturing score 19 and a transverse fracturing score 20 generally aligned with the corresponding scores 17 and 18 of the flap 9.

20 It will be noted that the transverse scores 18 and 20 of these flaps extend to aligned edges of the flaps when they are in folded position.

25 The outer closure flap 10 has a longitudinal fracturing score 21 aligned with or registering with the scores 17 and 19 of the flaps 9 and 11 and a fracturing score 22 along the line of its hinge connection to the container wall 1 from which it extends. It also has a hinging score 23 aligned with the scores 18 and 20 of the inner and intermediate flaps.

30 The wall 3 has a downwardly curved fracturing score 24 extending from its longitudinal fracturing score 19 to the adjacent corner of the container.

35 These closure parts are sealed together in overlapping relation, the sealing material serving to adhesively connect the break-out portions which when fractured constitute the pouring opening closure designated generally by the numeral 25 and having the tucking tongue 14 adapted to retain the pouring closure in closed position.

40 To open the pouring closure, the outer end of the break-out sections and the fracturing portion 26 of the front wall are collapsed between the thumb and a finger; an inward thrust on the part 26 and an upward pull frees the break-out sections along the fracturing lines leaving them connected to the container along the hinge score 23, as is shown in Figs. 1 and 2.

45 The pouring opening may be re-closed by 55 swinging the break-out opening closure down-

ward and tucking its tongue 14 within the side wall, the tongue being provided with a laterally projecting catch portion 27 which engages the adjacent edge of the inner flap, as shown in Fig. 7. This effectively retains the pouring opening closure in closed position, protecting the contents while permitting repeated pouring operations.

We have illustrated and described our invention in a practical embodiment thereof. We have not attempted to illustrate or describe other embodiments or adaptations which we contemplate for different types of cartons as it is believed that this disclosure will enable those skilled in the art to embody or adapt our invention as may be desired.

Having thus described our invention, what we claim as new and desire to secure by Letters Patent, is:

1. A dispensing container comprising walls provided with overlapping inner, outer and intermediate closure flaps adhesively secured together, the inner flap having a tucking tongue on one end thereof disposed within the container when the closure flaps are closed and constituting a pouring opening closure tucking flap, the overlapping closure flaps having adhesively connected break-out sections for providing a pouring opening and a closure therefor, the break-out section of the inner flap being defined by the swinging edge of the flap and by longitudinal and transverse fracturing scores, the intermediate flap having longitudinal and transverse fracturing scores registering with the fracturing scores of the inner flap, the wall from which the intermediate flap extends having a fracturing score extending from the outer end of the longitudinal fracturing score of the intermediate flap to the adjacent corner of the container, the outer flap having a fracturing score extending along the line of its connection to the container wall from which it extends and a longitudinal fracturing score aligned with the longitudinal fracturing scores of the inner and intermediate closure flaps and having a hinging score registering with the transverse scores of said inner and intermediate flaps, the said tucking tongue being extended beyond the inner side edge of the pouring opening to interlock therewith when the pouring closure is in closed position.

2. A dispensing container comprising walls provided with overlapping inner, outer and intermediate closure flaps adhesively secured together, the inner flap having a tucking tongue on one end thereof disposed within the container when the closure flaps are closed and constituting a pouring opening closure tucking flap, the overlapping closure flaps having adhesively connected break-out sections for providing a pouring opening and a closure therefor, the break-out section of the inner flap being defined by the swinging edge of the flap and by longitudinal and transverse fracturing scores, the intermediate flap having longitudinal and transverse fracturing scores registering with the fracturing scores of the inner flap, the wall from which the intermediate flap extends having a fracturing score extending from the outer end of the longitudinal fracturing score of the intermediate flap to the adjacent corner of the container, the outer flap having a fracturing score extending along the line of its connection to the container wall from which it extends and a longitudinal fracturing score aligned with the longitudinal fracturing scores of the inner and intermediate closure flaps

and having a hinging score registering with the transverse scores of said inner and intermediate flaps.

3. A dispensing container comprising walls provided with overlapping inner, outer and intermediate closure flaps adhesively secured together, the overlapping closure flaps having adhesively connected break-out sections for providing a pouring opening and a closure therefor, the break-out section of the inner flap being defined by the swinging edge of the flap and by longitudinal and transverse fracturing scores, the intermediate flap having longitudinal and transverse fracturing scores registering with the fracturing scores of the inner flap, the wall from which the intermediate flap extends having a fracturing score extending from the outer end of the longitudinal fracturing score of the intermediate flap to the adjacent corner of the container, the outer flap having a fracturing score extending along the line of its connection to the container wall from which it extends and a longitudinal fracturing score aligned with the longitudinal fracturing scores of the inner and intermediate closure flaps

20 and having a hinging score registering with the transverse scores of said inner and intermediate flaps.

4. A dispensing container comprising walls provided with overlapping inner, outer and intermediate closure flaps adhesively secured together, the inner flap having a tucking tongue on one end thereof disposed within the container when the closure flaps are closed and constituting a pouring opening closure tucking flap, the inner closure flap and the other overlapping closure flaps having adhesively connected break-out sections for providing a pouring opening and a closure therefor, the break-out sections being defined by substantially aligned scores, the wall from which the intermediate flap extends having a fracturing score extending across the break-out section of the intermediate flap, the outer flap having a hinging score at its inner end, the other scores being fracturing scores, said hinging score of the outer flap constituting the sole hinge means for the closure for the pouring opening.

5. A dispensing container comprising walls provided with overlapping inner, outer and intermediate closure flaps adhesively secured together, the inner flap having a tucking tongue on one end thereof disposed within the container when the closure flaps are closed and constituting a pouring opening closure tucking flap, the inner closure flap and the other overlapping closure flaps having adhesively connected break-out sections for providing a pouring opening and a closure therefor, the break-out sections being defined by substantially aligned scores, there being a fracturing score extending across the front of the break-out section of the intermediate flap, the outer flap having a hinging score at its inner end, the other scores being fracturing scores, said hinging score of the outer flap constituting the sole hinge means for the closure for the pouring opening, the said tucking tongue being extended beyond a side edge of the pouring opening to interlock therewith when the pouring closure is in closed position.

6. A dispensing container comprising walls provided with overlapping inner, outer and intermediate closure flaps adhesively secured together, the inner flap having a tucking tongue on one end thereof disposed within the container when the closure flaps are closed and constituting a pour-

ing opening closure tucking flap, the inner closure flap and the other overlapping closure flaps having adhesively connected break-out sections for providing a pouring opening and a closure therefor, the break-out sections being defined by substantially aligned scores, there being a fracturing score extending across the front of the break-out section of the intermediate flap, the outer flap having a hinging score at its inner end, the inner closure flap having a fracturing score parallel to and adjacent said hinging score.
